H F Mann

Mower

No 15.013

Patented June 3, 1856

UNITED STATES PATENT OFFICE.

HENRY F. MANN, OF WESTVILLE, INDIANA.

IMPROVEMENT IN HARVESTER-FRAMES.

Specification forming part of Letters Patent No. 15,013, dated June 3, 1856.

To all whom it may concern:

Be it known that I, HENRY F. MANN, of Westville, in the county of Laporte and State of Indiana, have invented certain new and useful Improvements in the Construction of Harvester-Frames; and I do hereby declare the following to be a full, clear, and exact description of the same, reference being had to the accompanying drawings, making a part thereof, in which—

Figure 1 represents a view from one side of the machine. Fig. 2 represents a view from the opposite side thereof. Fig. 3 represents a top plan.

Similar letters, where they occur in the several figures, denote like parts in all.

I am aware that harvester-frames have been inclined downward in front of the supporting and driving wheel, and where the cutter-bar was also in front of the said wheel. This not only makes the tongue-connection awkward, but, the whole weight being forward of the wheel, throws the machine out of proper balance; but in the machines above referred to there is no inclination of the pinion-shaft, which I deem a material point in the construction of the frame. Such form of frame I lay no claim to.

The nature of my invention consists in inclining that portion of the frame which is in rear of the supporting or driving wheel so as to give a good bearing to the pinion-shaft, and which enables me to group the driving machinery in a compact form, as will be explained.

To enable others skilled in the art to make and use my invention, I will proceed to describe the same with reference to the drawings.

A represents the main supporting-wheel, the journals of which run in suitable bearings on the two side pieces, B C, of the frame. These side pieces, B C, in advance of the journals of the wheel A, are parallel with each other, and lie in nearly a horizontal position, being united by an end piece, D, at their front ends; but in rear of the journals they both dip at different inclinations toward the ground. The one, B, Fig. 2, inclines down, and is fastened immediately to the finger-bar E. The other, C, Fig. 1, is first curved downward and then inclines slightly, and is supported by an upright, F, which is bolted to it and to the finger-bar E. A brace, H, extends from the lower

end of the upright F to the side piece C. Another brace, G, runs from the finger-bar E to the front end of the frame, and this constitutes the frame.

On one of the journals of the main wheel A is a cog-wheel, I, which takes into a pinion, a, on the pinion-shaft b, and gives motion to said shaft. The shaft b has its bearings on the side piece C, and has the same or nearly the same inclination as said side piece, for a purpose to be presently described. On the extreme rear end of the shaft b is a bevel-gear, J, which meshes with and gives motion to a pinion, c, on the crank-shaft d, to the crank on which shaft the cutter-bar is connected. The crank-shaft d is driven at a very high velocity, and unless made extremely heavy is liable to spring or vibrate by its speed, and such springing almost invariably ends in breaking the drive-wheel or pinion. The object therefore in inclining the side piece C is to give the pinion-shaft b not only a permanent bearing immediately upon said side piece, but also to dip said shaft so as to bring its wheel J in close proximity to the crank itself, where the pinion c is arranged. Thus a compact form is given to the gearing, and a short crank-shaft may be used, which of course is less liable to spring than a long one.

e is a roller behind the finger-bar to keep the bar slightly raised from the ground.

K is the tongue by which the machine is drawn.

By constructing the frame as herein described I make a strong, well-balanced machine with an exceedingly light frame, and group the whole of the driving machinery into a very compact form.

Having thus fully described the nature of my invention, what I claim therein as new, and desire to secure by Letters Patent, is—

Inclining the rear portions of the side pieces, B C, so that the shaft b may lie upon and have the same dip with the one C, on which it is supported, for the double purpose of giving said shaft a firm support and to bring its drive-wheel J close down to the pinion on the crank-shaft, substantially in the manner and for the purposes set forth.

H. F. MANN.
